UNITED STATES PATENT OFFICE.

CHARLES B. WEBSTER, OF FALL RIVER, MASSACHUSETTS, ASSIGNOR TO JAMES K. LANNING, OF FALL RIVER, MASSACHUSETTS.

MACHINE FOR COVERING ELASTIC FILAMENTS.

Application filed August 7, 1924. Serial No. 730,603.

This invention relates to the manufacture of elastic thread such as is used in woven and knitted elastic fabrics, said thread comprising an elastic or distensible filament of soft rubber which is coated or covered with one or more layers of yarn wound in close spirals around the cord to form a protective exterior, while allowing the finished cord or thread to readily stretch under tension.

It is the object of the present invention to provide a yarn-winding mechanism adapted to perform this operation and capable of turning out a product at materially higher speeds than heretofore was obtainable with the devices used for that purpose.

Generally speaking, the invention embraces the combination of a rotary yarn package properly associated with a traveler ring and its yarn-guiding traveler so disposed as to wind closely around the elastic filament as the filament is fed axially through the interior of the yarn package and of the traveler ring.

This and other features of the invention will be particularly described in the following specification and will be defined in the claims hereto annexed.

In the accompanying drawings I have illustrated a construction and arrangement embodying the principles of this invention, in which:

Figure 1 is a front elevation showing the end portion of a machine for thus covering an elastic filament.

Figure 2 is an end elevation of one side or half of such a machine.

In the practice of this invention, according to the specific form illustrated in the drawings, I employ a construction somewhat analogous to a spooler or spinning frame comprising vertical standards or upright frames 1, to which is secured a longitudinal horizontal spindle rail 2, in which are mounted any suitable form of bearing members, shown conventionally at 2^a, to rotatably support a hollow or tubular spindle 3 on which is mounted a yarn package preferably in the form of a spool or bobbin 4, on which is wound a copious supply of yarn.

Each spindle is provided with a driving whorl 3^a around which passes the quarter-turn driving band 6^a which also passes around the driving drum or cylinder 6

mounted on a rotary shaft 6^b, in accordance with well-known spinning practice.

Another horizontal rail 7, extending longitudinally of the machine and supported by the uprights 1, is provided at intervals with perforations or openings concentric with the axis of rotation with the spindle beneath it, and adjacent to and surrounding these openings is mounted a traveler ring 8, of well known construction, on which is placed a traveler or clip 8^a through which the end of yarn from the yarn package 4 is carried before the yarn is attached to the elastic filament indicated at x—x, which is fed axially through the interior of the yarn package and of the traveler ring.

It will be understood that any desired number of spools and spindles with corresponding traveler rings may be mounted side by side on a frame of this construction, and that this arrangement, like a spinning frame, may be duplicated on the opposite side of the machine.

Any suitable feeding means for feeding the elastic filament through the yarn package and its traveler ring may be employed. In this case a longitudinal rotatable beam 10 carries the requisite number of elastic filaments coiled or wound on it to supply a filament for each yarn-winding unit. As these beams need not be equal in length to the length of the winding frame, I provide guiding means which, in this case, comprise a longitudinal rod 11 provided with a guiding block 11^a arranged in the transverse planes that intersect the axes of the different spindles so as to spread the filaments apart

to guide them into position to pass up through their respective yarn-carrying spindles so that the filaments may be fed axially up through each yarn package without rubbing against the interior of the yarn carrier. There is also provided a longitudinal guide-rod 12 with its outermost surface disposed directly in line beneath the axial centers of the spindles, as shown in Figure 2. The beam shaft or journals 10^a rest in bearing recesses formed in the middle portion of the uprights 1, of the frame, and the frictional resistance of rotation serves to put the requisite tension upon the beam. This tension may be varied by means of a weighted brake arm 14 pivoted so as to engage the shaft 10^a of the rotatable beam, and carrying an ad-

justable weight 14^a whose adjustment along the beam will vary the frictional retardation of the rotating beam.

Elastic filaments are drawn through the 5 winding apparatus by means of a rotated beam or spool 15 provided with a friction clutch 15^a engaging a cooperating clutch member 16, splined on the shaft 17, and normally pressed into frictional engagement by 10 means of a helical spring 18 coiled around the shaft and the hub of the friction driving member 16.

In order to distribute each covered cord laterally on the beam I provide a longitudinal reciprocatory guide rod 24, provided with guide-eyes in the form of pigtails 24^a through which the respective cords are passed. The guide rod 24 is reciprocated by any suitable mechanism, and in this case

20 I have shown, secured to the end of the shaft 17, a worm 19 which causes the slow rotation of a crank shaft 21, through its engagement with a worm wheel 20 on said shaft 21. The crank pin 22^a of the crank 22 is connected with a link 23 which engages a pivot pin 23^a, carried by the slide rod 24 so as to cause a slight to and fro movement of the covered cord longitudinally of the spool.

30 To keep the elastic cord centered I provide a guide bar 25 with fixed guides 25^a arranged coaxially with the rotary spindles and their associated traveler rings, and thus the upward traveling cords are, at all

35 times, guided centrally of the hollow spindles; while their upper ends are shifted longitudinally to proper wind or coil on the receiving beam.

If it be desired to wind only one layer of 40 yarn on the elastic filament a single horizontal row of the yarn packages with associated traveler rings will suffice. Often, however, it is desired to wind on one or more additional layers and in the present 45 instance I have shown two exactly similar winding arrangements with one superimposed to register with the other.

As the second layer is wound on a slightly 50 larger diameter than the first layer, since it must be wound outside of the first layer, I prefer to drive the yarn-carrying spindles of the upper row at a somewhat higher speed than is imparted to the spindles of the lower row.

55 In the apparatus shown the driving shaft 6^b is the shaft forming the support for the lower drum and is itself driven by a conveniently disposed pulley 6^c. Any suitable means may be employed for transmitting 60 the proper rotative motion to the upper drum shaft 60, and in the present case this is done by means of a sprocket chain 61 passing around sprocket wheel 6^c on drive shaft 6^b, and sprocket wheel 60^c on upper 65 drive shaft 60, the latter being of somewhat

smaller diameter than the former to increase the speed of rotation of the upper drum shaft.

In order to rotate the upper and lower rows of spindles in reverse directions in order to cross-wind the two layers on the elastic filaments, the driving bands 6^a are given a right hand quarter turn in the one case and a left hand quarter turn in the other case so as to produce this result. It will, 75 of course, be understood that any desired number of aligned yarn carriers and traveler rings will be used, but ordinarily two rows, one superimposed above the other, will be sufficient.

What I claim is:

1. In a machine for covering elastic filament, the combination with a rotary yarn-carrier having an axial bore for the passage of an elastic filament, a yarn package 85 mounted concentrically upon said yarn-carrier to be rotated therewith, a traveler ring and traveler mounted above the level of the top of said yarn package and its supporting carrier to leave a free unobstructed path for 90 the yarn passing from the traveler to the elastic filament, frictionally driven means for feeding said elastic filament centrally through the yarn carrier, the yarn package and the coaxial traveler ring, and a centralizing guide surrounding the elastic filament 95 above the level of the winding point of the yarn.

2. In a machine for winding yarn on an elastic filament, the combination of a rotary 100 supply beam, a rotary winding beam, frictionally driving means for rotating said winding beam, means for regulating the frictionally driving means to vary the winding tension on the filament, an axially bored 105 rotary yarn-package carrier concentrically mounted to surround the filament as it passes from one beam to the other, a traveler ring and traveler mounted concentrically with the filament between the yarn 110 package and the winding-on beam to allow free movement of the yarn passing from the yarn package through the traveler to the filament and a centralizing guide surrounding the filament beyond the winding 115 point of the yarn upon the filament.

3. In a machine for covering elastic thread, the combination of a series of hollow yarn-carrying rotary spindles axially aligned with a corresponding series of traveler rings carrying yarn-engaging travelers, means for feeding a series of elastic filaments axially through said spindles and traveler rings to permit the winding of the 120 yarn thereon, said means embracing a frictionally driven winding beam and guide for maintaining the filaments in axial relationship to the spindles and traveler rings, substantially as described.

4. In a machine for covering elastic 130

thread, the combination of a series of yarn-carrying hollow spindles, a series of traveler rings and yarn-engaged travelers coaxially mounted above said spindles, means for 5 feeding a series of elastic filaments axially through the spindles and traveler rings including a rotatable winding beam, and means for shifting the filaments lengthwise of the winding beam while still permitting them to 10 travel axially through the spindles and rings, substantially as described.

5. In a machine for covering elastic thread, the combination of a series of hollow rotary yarn carriers, a series of overhead traveler rings with their yarn-controlling travelers adapted to be dragged around by the revolving yarn, means for drawing a series of elastic filaments axially through the yarn carriers and the traveler rings, a 20 rotatable winding beam, and a reciprocatory guide bar arranged to engage the filaments in spaced relation and distribute them lengthwise of the winding beam as the latter revolves, substantially as described.

25 6. In a machine for covering elastic thread, the combination of means for feeding a series of elastic filaments in spaced

relation, plural series of hollow rotary yarn-carrying members arranged to surround said filaments, and a series of revoluble yarn-engaging guides arranged to be driven by the revolving yarn passed through them and thereby wind the yarn around the filaments and means for driving one set of 30 yarn-carrying members at higher speed 35 than the preceding set to compensate for the increased thickness of the elastic thread, substantially as described.

7. In a machine for covering elastic thread, the combination of means for feeding a plurality of elastic filaments from one beam to another, a series of hollow rotary yarn carriers through which the separate filaments are fed, a series of yarn-revolved travelers arranged to wind the yarn around the respective filaments, and another series of similar rotary yarn carriers and travelers aligned with the first series and revolved in the reverse direction, substantially as described. 40 45

In witness whereof, I have subscribed the above specification.

CHARLES B. WEBSTER.
